UNITED STATES PATENT OFFICE.

WILLIAM EHRHARDT, OF UNION, HUDSON COUNTY, NEW JERSEY, ASSIGNOR
OF ONE-HALF TO GEORGE A. CONNER, OF NEW YORK, N. Y.

SAFETY DEVICE FOR ELEVATORS.

SPECIFICATION forming part of Letters Patent No. 577,649, dated February 23, 1897.

Application filed January 4, 1895. Serial No. 533,866. (No model.)

To all whom it may concern:

Be it known that I, WILLIAM EHRHARDT, a citizen of the United States, residing in the town of Union, county of Hudson, and State 5 of New Jersey, have invented a new and useful Automatic Electromagnetic Safety Device for Elevators or Hoistways, of which the following is a specification.

My invention relates to safety devices for 10 hoistways, elevators, and elevator-shafts such as are used in office-buildings, hotels, warehouses, &c.

The object of the invention is to provide 15 means whereby it is made impossible to open the elevator-door when the car is out of proper position or to start the car until the car-door is closed and fastened, thereby removing the liability of accidents to persons attempting to enter or leave an ascending or descending 20 car through a partially-closed door. Furthermore, the elevator cannot be started in either direction until all the doors or openings in the entire shaft are closed and fastened.

The attendants or operators of elevator- 25 cars often open the doors leading to the car before the car has entirely reached the landing and is still in motion, and passengers commence to leave or enter the car while it is still in motion. Many accidents of a serious na- 30 ture have occurred in this way.

Another object of the invention is to so construct the device that it will be exceedingly simple and may be applied expeditiously, conveniently, and cheaply to any elevator car 35 and shaft.

To this end the invention consists in locating a brake-shoe or friction device above the highest point to which the car ascends in such a position as to operate against a brake-wheel 40 fastened to the controller-rope pulley, said brake-shoe or friction device being brought into action and controlled by an electric current, the circuit of which is opened and closed by the opening and closing of doors at the 45 various landings.

It further consists in providing the doors at the various landings with electromagnetic locks that are exceedingly simple in construction and which can be applied to any of the 50 elevator-doors in a few minutes. These elec-

tromagnetic locks are controlled by a boss fastened to the elevator-car. Arriving at a floor-level, contact is made with a wall-spring placed in an electric circuit, whereby a hanging piece or pendulum, which is part of the 55 electromagnetic lock, is attracted to the magnet and out of the path of the latch, which permits the latch to be raised and the door to be opened.

It also consists in a combination of these 60 two sets of devices, whereby both the foregoing results are automatically accomplished.

It further consists in the novel construction and combination of the several parts, as will be hereinafter fully set forth, and pointed out 65 in the claims.

By referring to the various drawings that accompany this specification, and of which they form a part, the manner of arriving at the above results will be seen and understood. 70

Figure 1 is a perspective view of an elevator-shaft with my invention applied thereto. Fig. 2 is a diagrammatic view of the same, and Fig. 3 is a detail.

Similar letters in the various drawings refer to similar parts.

Fig. 1 illustrates an elevator or hoistway consisting of three floors, though I do not limit myself to any number of floors, as my invention can be used on elevators of from one 80 floor up to any number of floors.

A represents the elevator-car, and it has arrived at the top or third floor.

At B is seen the shaft or well of the second floor, the door being broken away to show 85 frame C, which contains a spring or push-button D. The frame is fastened to the side of the well and the spring D projects through the frame C.

At E is shown a pin in position to be struck 90 by the door when closed, and at E' a part of the framework has been removed to show the contact fastened to the pin and which is part of it.

F represents an electromagnetic lock. a 95 are the electromagnets; b, the hanging piece or pendulum, which is pivoted at c by a brass or non-magnetic pin and swings or rotates freely on said pin. When in its normal position, it hangs over the latch and prevents 100

same from being raised, and consequently the door cannot be opened. Fastened to the side of the car A is a tapered boss or projection G. This boss is tapered at both ends, so it can 5 rub against any spring it may come in contact with on either the ascent or descent of the car to which it is fastened. This boss is so placed that when the car has arrived at a floor-level it pushes in spring D, which closes 10 an electrical circuit in which it is placed and of which it forms part. The electric current now flows around the electromagnets a, which energizes them, causing the hanging piece b to be attracted and permits the latch to be 15 lifted and the door opened. The hanging piece b will be held in this position as long as the elevator-car remains on a floor-level. At the upper floor in Fig. 1 the boss G is shown in contact with the spring D and the hanging 20 piece b is also shown attached to the electromagnet a by the induced magnetism due to the current passing around them. Fig. 1 also shows the door-pin E, which has been released by opening the door, and shows the contacts 25 touching. Through these contacts an electrical circuit is made and the current energizes electromagnets I, placed at the top of the elevator-shaft. These electromagnets attract a lever J. To the opposite end of said 30 lever is securely fastened a brake-shoe K. This brake-shoe K engages a brake-wheel L, fastened to the controller-rope pulley M, and prevents the controller-rope from being moved as long as the door is open. 35 When the door is closed, the pin E will be flush with the framework of the elevator-shaft, the contacts at E' will be separated, the electric circuit will be broken, the electromagnets will release the lever J, and the 40 brake-shoe K, fastened to the opposite end, will not be in contact with the pulley which is part of the controller-rope pulley M, allowing the rope to be freely pulled in either direction. If the door is not shut or only partly 45 shut, the circuit will still be closed through the contacts shown at E' and the attendant cannot operate the controller-rope. He must absolutely break the contact by shutting the door and opening the circuit through the contacts shown at E'. 50

In Fig. 2 is shown the manner of making electrical connection with the electromagnetic locks F. Pins E, embedded in the framework of the elevator-shaft and which are operated 55 by the opening and closing of the elevator-doors and the wall contact-springs D, are shown in this figure. If there is an electrical plant in the building, a small continuous current can be shunted through these devices or 60 an independent source of electricity, as, for instance, galvanic batteries, can be used. I prefer a three-wire system (shown in Fig. 2) for connecting up the locks and springs as one length of wire is saved. Two separate circuits can, however, be used, one circuit to 65 actuate the locks and the other the brake

device at the top of shaft, each circuit to have an independent set of batteries.

By referring to Fig. 2 my manner of connecting up will be clearly understood. N 70 represents a source of electricity, as, for instance, a set of galvanic cells. A wire, No. 3, is connected to terminal d of the cells and extends to the floor on which is situated the electromagnetic brake, and is connected to 75 the wire e of the electromagnets. The other end of magnet-wire e' is connected to the middle wire No. 2. One end of the wire-terminal of all the door-pins E is fastened to the wire No. 1 and all the other ends to wire 80 No. 2. When a circuit is made by releasing any of the door-pins E, the current passes through the contacts into wire No. 2, up around the electromagnets at the top of the building and into wire No. 3, through the 85 cells N, up through wire No. 1 to the springs. The current will flow through this circuit as long as a door-pin remains released.

In connecting the wall-springs I proceed as follows: I connect one terminal of all of 90 the wall-springs D to wire No. 1. The other terminal I connect to one terminal of the electromagnetic lock located on the same floor. The other terminals of electromagnetic locks are all connected to wire No. 3. This completes the circuit from the cells through the 95 wall-spring to the lock and back again to the cells.

Fig. 3 illustrates an electromagnetic lock with the cover removed. a a are the electromagnets. b is the hanging piece, c the non-magnetic pin, and H the latch. In the drawings the latch is seen in the lock with the hanging piece b over it in its normal position. This prevents the latch from being raised, and 100 hence the door cannot be opened. When an electric current is made to travel through the electromagnets, the hanging piece b is attracted to the magnets and remains in that 105 position as long as the current continues to traverse said magnets. The dotted lines show position of hanging piece when attached to electromagnets. The latch can now be raised and door opened.

What I claim as my invention, and desire 110 to secure by Letters Patent, is—

1. The combination with the elevator-car and the shaft-door and its lock and starting-rope, of a boss, as G, fastened to the exterior of the car, wall-springs, as D, fastened to the 120 elevator well or shaft, electrical connections and a source of electricity, whereby said boss, when the elevator-car has arrived at a floor-level closes an electrical circuit, rendering operative said lock and permitting the door to 125 be opened, substantially as described.

2. The combination, with the elevator-car having a boss or projection thereon and the doors at the several landings, of electromagnetic locks, each consisting of a latch on the 130 door, an electro magnet or magnets and a hanging piece or pendulum, and electrical connec-

tions whereby the car, upon arriving at a floor level, causes said pendulum to be attracted to the magnet or magnets, permitting the latch to be lifted and door opened, substantially as described.

3. The combination of an elevator-car having a boss or projection as G, wall-springs as D fastened to the well or elevator-shaft, a pulley around which said rope passes, and a brake-wheel fastened to said pulley, elevator-starting or valve rope, and the doors at the several landings, of a brake-shoe as K, electromagnetic locks for the doors, each consisting of a latch on the door, and electro magnet

or magnets, and a hanging piece or pendulum 15 and electrical connections operated by the boss or projection fastened to the car to attract or release the hanging piece or pendulum to or from the electro magnet or magnets which permits the door to be opened or closed, 20 and by the doors to operate the brake-shoe to engage or release the brake-wheel, substantially as described.

WILLIAM EHRHARDT.
